UNITED STATES PATENT OFFICE.

JOHN L. SIMPSON, OF HAMILL, PENNSYLVANIA.

CHECKREIN-HOOK.

SPECIFICATION forming part of Letters Patent No. 636,927, dated November 14, 1899.

Application filed July 16, 1898. Serial No. 686,189. (No model.)

To all whom it may concern:

Be it known that I, JOHN L. SIMPSON, residing at Hamill, in the county of Indiana and State of Pennsylvania, have invented a new and useful Checkrein-Hook, of which the following is a specification.

This invention relates generally to a harness attachment, and more particularly to a checkrein-hook adapted for attachment to a harness-saddle; and the object of the invention is to provide an exceedingly cheap and simple device having a spring-tongue for holding the strap beneath the hook; and another object of the invention is to provide an easy and practical method of attaching the said spring-tongue.

With these objects in view my invention consists, broadly, in a longitudinally-slotted checkrein-hook and a spring-tongue pivoted in said slotted hook and adapted to normally hold the tongue in a closed or locked position.

The invention consists also in certain details of construction and novelties of combination, all of which will be fully described, and pointed out in the claims.

In the drawings forming a part of this specification, Figure 1 is a perspective view of my checkrein-hook attached to a harness-saddle. Fig. 2 is a vertical longitudinal section, the 30 spring-tongue being shown in elevation. Fig. 3 is a top plan view. Fig. 4 is a sectional view showing a slight modification, and Fig. 5 is a top plan view of said modification.

In carrying out my invention I employ a hook A, which is attached to the jockey B of the harness-saddle by means of a bolt C in the usual or ordinary manner. The upper member of the hook A is slotted longitudinally, as shown at D. A tongue E is pivoted 40 within the slot near the forward end by means of a pin F passing transversely through the hook and tongue.

In Figs. 2 and 3 I have shown the tongue as constructed of a single piece of spring-wire, 45 while in Figs. 4 and 5 I have shown it formed of wrought or cast metal and normally held

down by means of a spring G, which surrounds the pivot-pin and bears upon the tongue and hook. The tongue is curved downwardly, as shown, until it bears upon the 50 head of the securing-bolt, and the free end is then carried upward and normally rests in the rear end of the slot, so that when the checkrein is passed in or out the tongue is raised and finds ample space in the slot in 55 the hook, and by having the free end rest within the slot any lateral displacement of said hook is prevented.

The operation and advantages of my invention are apparent to every one skilled in the 60 art to which my invention relates, and it will be understood that slight changes of construction can be made without departing from the broad principle of the invention.

Having thus fully described my invention, 65 what I claim as new, and desire to secure by Letters Patent, is—

1. A checkrein-hook having its upper member slotted longitudinally and a spring-actuated tongue pivoted within the slot near the 70 forward end, said tongue being curved downwardly and then upwardly, the free end resting also within the slot near the rear end, substantially as shown and described.

2. In a checkrein-hook, a hook member A, 75 having its upper portion slotted longitudinally, a substantially V-shaped tongue, pivoted in said slot, the free end being adapted to extend through the slot for the purpose set forth.

3. In a device of the character described, the combination with the hook A having an elongated slot in the upper portion thereof, of a spring-pressed, substantially V-shaped tongue pivoted at one end in said slot and 85 adapted to project through the same, substantially as described.

JOHN L. SIMPSON.
